UNITED STATES PATENT OFFICE.

FRANK RYLANDER, OF DUMONT, COLORADO.

DUST-COLLECTOR FOR ROCK-DRILLS.

1,131,009.

Specification of Letters Patent.

Patented Mar. 9, 1915.

Application filed March 17, 1914. Serial No. 825,278.

To all whom it may concern:

Be it known that I, FRANK RYLANDER, citizen of the United States, residing at Dumont, county of Clear Creek, and State 5 of Colorado, have invented certain new and useful Improvements in Dust-Collectors for Rock-Drills; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specifica- 15

My invention relates to improvements in dust collectors for rock drills, my object being to provide a device of this character containing several improvements over constructions heretofore employed. My construction is of the class in which a dust collecting hood surrounding the drill hole and engaging the breast of the rock is held in place independently of the drill, as by a 20 standard which is connected with the hood at one extremity, while its other extremity 25 engages the bottom of the tunnel or other suitable stationary support.

One novel feature of my improvement 30 consists in making the standard hollow and using it as a conduit through which the dust or rock cuttings entering the hood from the drill hole, pass downwardly and are discharged at the lower extremity of the stand- 35 ard, which is open for the purpose. The bottom or lower extremity of the hood consists of a disk which is engaged by one extremity of a spiral spring whose opposite extremity bears against a relatively large 40 ring into which the outer extremity of the hood is formed, the material or fabric of the hood being turned back upon itself and secured and the loop thus formed being filled 45 with a packing of some suitable material. 50 This ring at the outer extremity of the hood forms a seat for one extremity of the spiral spring, which acts thereon to maintain the hood closely against the breast of the rock to prevent the escape of cuttings in the form 55 of dust. The difficulty of allowing the rock cuttings to escape in the form of dust is well understood, since it is impossible for workmen to long endure without serious injury, the breathing of air contaminated with this dust, as it gradually injures the lungs and finally brings on tuberculosis. The disk at

the bottom of the hood is provided with an opening which is surrounded by an inwardly projecting collar, while the bottom of the disk is reinforced and circumferentially grooved to receive a flange formed on the top of a sleeve which has a swivel connection with the disk by virtue of this reinforcement. The drill steel passes through this sleeve, which is provided with an opening shaped to conform to the general shape of the steel whereby the sleeve rotates with the drill steel while the latter turns freely in the rigid bottom of the hood. Within the sleeve and surrounding the drill steel, is 60 a gasket or bushing which is held in place by a second sleeve exteriorly threaded to engage the interior threads of the first named sleeve. The second sleeve is screwed tightly against the gasket to form a dust 65 tight joint around the drill steel. By virtue of this construction the drill steel, together with the two sleeves and the gasket, are allowed to turn freely within the disk 70 of the hood. It is well known that in rock 75 drilling, it is necessary that the drill steel should be given a partial rotation after each blow is delivered, in order to prevent the steel from sticking in the drill hole. By virtue of the construction just described, 80 the drill steel is allowed to perform this operation and still maintain a dust tight joint where it passes through the bottom of the 85 hood.

Having briefly outlined my improved 90 construction, I will proceed to describe the same in detail, reference being made to the accompanying drawing, in which is illustrated an embodiment thereof.

In this drawing, Figure 1 is an elevation 95 of a rock drill equipped with my improved dust collector, the breast of the rock being shown in section cutting the drill hole, the drill bit being shown in place. Fig. 2 is a fragmentary sectional view of the same construction but shown on a larger scale. Fig. 3 is a cross section taken through the hood on the line 3—3, Fig. 2. Fig. 4 is a section taken on the line 4—4, Fig. 2, looking upwardly, or in the direction of the arrow 4, 100 Fig. 2. Fig. 5 is a fragmentary section taken on the line 5—5, Fig. 3, illustrating one of the fastening devices for securing the spring to the disk of the hood. Fig. 6 is a top plan view of the swiveled sleeve shown 105 in detail. This view is obtained by looking in the direction of the arrow 6, Fig. 7.

Fig. 7 is a section taken on the line 7-7, Fig. 6. Fig. 8 is a plan view of the gasket or bushing employed in connection with the swiveled sleeve for making a tight joint 5 around the drill steel. Fig. 9 is a section taken on the line 9-9, Fig. 8.

The same reference characters indicate the same parts in all the views.

Let the numeral 5 designate the hood of 10 my improved device whose body portion is composed of canvas 6 or some other suitable flexible material. The outer extremity of the fabric of the hood is formed into a circular loop or hollow ring 7, which is filled 15 with a packing material 8 which is sufficiently yielding to fit the breast 9 of the rock closely around the drill hole 10, regardless of ordinary irregularities, in order to prevent the escape of the rock cuttings at 20 the breast of the rock, where they leave the drill hole.

The lower extremity of the fabric 6 of 25 the hood is secured as shown at 12, to the outer edge of the disk 13, which constitutes the bottom of the hood. The outer edge of 30 this disk is grooved as shown at 14 and the lower extremity of the fabric of the hood is applied thereto and secured in place in any suitable manner, as by means of a small wire 15 which is passed around the material 35 of the hood on the outside and secured in place by twisting the extremities of the wire together, as shown at 16, whereby the wire is tightened upon the hood and holds the latter securely in contact with the disk.

Between the disk 13 and the outer extremity of the hood is located a spiral spring 17, which is under sufficient tension to hold the outer extremity of the hood tightly 40 against the breast of the rock, when the hood is held in place by a suitable support. The disk or bottom of the hood is provided at one side of its center with an opening 18 which is surrounded by an interiorly projecting collar 19 through which the drill 45 steel 20 passes. To the lower surface of the disk 13 is applied the upper extremity 21 of a sleeve 22, its outer extremity being equipped with an exteriorly projecting flange 50 23 which engages a groove 24 of counterpart shape formed in a reinforcement 25, applied to the lower surface of the disk. This sleeve extends downwardly through an opening 26 in the reinforcement 25 and in its upper part 55 is located a gasket or bushing 27, composed of some suitable soft or elastic material, which is held in place by means of a second sleeve 28 which is exteriorly threaded to engage the interior threads of the first named 60 sleeve. The sleeve 28 is screwed into a sleeve 22 and forced tightly against the gasket 27 whereby the latter is expanded both outwardly and inwardly to form a disk tight joint around the drill steel. By virtue of 65 this construction the two sleeves 22 and 28,

together with the gasket and drill steel, are allowed to rotate in order that the partial rotary movement of the drill steel within the hood may be accomplished without interfering with the proper performance of 70 the dust collection function of the structure.

The hood is supported in place against the breast of the rock by means of a hollow standard 29, which consists of two telescoping parts 30 and 31, said parts being lengthwise adjustable and locked in the desired position of adjustment by means of a set screw 32 passing through an opening 33 formed in the reinforced upper extremity 34 of the standard member 31. The lower extremity of this standard is pointed as shown at 35, in order that it may be easily caused to indent the rock for the purpose of maintaining the standard securely in place when adjusted with reference to the drill mechanism, the latter being designated by the numeral 36. (See Fig. 1).

As illustrated in the drawing, the disk is provided with a relatively short depending tubular member 37, whose upper extremity 90 is made fast to the disk and whose lower extremity is tapered as shown at 38 to fit tightly into the upper reinforced extremity 39 of the upper member 36 of the standard. By virtue of this construction the standard 95 may be readily detached from the member 37 by simply loosening the set screw 32 and moving the member 29 downwardly into the member 31 far enough to accomplish this purpose. 100

In order to tightly secure the spring against the disk of the hood, the disk is provided with fastening devices 40 which as illustrated in the drawing, consist of short stems 41 which pass through openings 42 105 formed in the outer edge of the disk and passing also through registering openings 43 formed in the disk reinforcement 25. This stem passes below the reinforcement and is threaded as shown at 44 to receive 110 a fastening nut 45. The upper extremity of the stem is equipped with a part 46 extending at right angles to the stem and slightly concaved at its outer extremity as shown at 47, to engage the lowermost convolution 48 115 of the spring. As illustrated in the drawing, two of these fastening devices are shown, though it is evident that any other desired number may be employed. When the upper extremity of the fastening device 120 is properly adjusted upon the lowermost convolution of the spring, it is secured in place by tightening the nut 45. It also is evident that by loosening this nut, the fastening device may be quickly adjusted to release the spring. 125

From the foregoing description, the use and operation of my improved construction will be readily understood. Assuming that the hood is supported in place against the 130

breast of the rock and that the drilling machine is mounted substantially as illustrated in Fig. 1, the drill steel being passed through the hood and the gasket, compressed by the 5 sleeve 28 to form a tight joint around the drill steel, as the drill operates, the rock cuttings from the drill hole are passed downwardly into the hood and pass thence through the tubular member 37 into the hole 10 standard and downwardly therethrough and escape at the opening 49 of the lower extremity of the standard and located just above the pointed end thereof. The rock cuttings, after being guided downwardly 15 through the standard, will quietly pass therefrom through the opening 49 without forming any dust. In this manner, the impregnation of the air by the dust resulting from the rock cuttings is obviated and the difficulty heretofore explained, overcome. 20

Having thus described my invention, what I claim is,

1. A dust collector for rock drills, comprising a hood and supporting standard connected with the hood and formed hollow to permit the escape of the rock cuttings. 25

2. A dust collector for rock drills, comprising a hood having a shoulder at its outer extremity, a rigid bottom and an expanding 30 spring located between the bottom and the shoulder, the bottom having an opening through which the drill steel passes and a second opening for the escape of the rock cuttings, and a supporting standard communicating with the bottom of the hood and having a passage registering with the second opening for guiding the rock cuttings downwardly therethrough. 35

3. A dust collector for rock drills, comprising a hood having a shoulder at its outer extremity, a rigid bottom and an expanding spring located between the bottom and the shoulder, the bottom having an opening through which the drill steel passes and a second opening for the escape of the rock cuttings, and a supporting standard communicating with the bottom of the hood and having a passage registering with the second opening for guiding the said rock cuttings downwardly therethrough, the bottom being also provided with a collar projecting therefrom inwardly around the drill steel to prevent the rock cuttings from entering the bottom opening through which the steel 50 passes. 55

4. A dust collector for rock drills, comprising a hood having a shoulder at its outer extremity, a rigid bottom, an expanding spring located between the bottom and the shoulder, the bottom having an opening through which the drill steel passes, the said opening being surrounded by an inwardly projecting collar, the bottom also having a second opening for the escape of the rock 60 cuttings, an exteriorly located sleeve swiv- 65

eled on the bottom of the hood and having an opening shaped to approximately fit the drill steel and rotatable therewith, while allowing the steel to pass freely therethrough in the direction of its axis, a gasket located 70 within the sleeve and also surrounding the drill steel, and a second sleeve threaded into the first sleeve and acting on the gasket to form a dust tight joint around the drill 75 steel.

5. A dust collector for rock drills, comprising a hood having a shoulder at its outer extremity, a rigid bottom, an expanding spring located between the bottom and the shoulder, the bottom having an opening 80 through which the drill steel passes, said opening being shaped to allow the drill steel to rotate therein as well as pass therethrough, and a second opening for the escape of the rock cuttings, means applied exteriorly to the bottom of the hood to form a dust tight joint, the said means being rotatable with the drill steel, and a hollow supporting standard connecting with the bottom of the hood to allow the rock cuttings to enter 85 as they pass through the second opening in the bottom, substantially as described. 90

6. A dust collector for rock drills, comprising a hood composed of flexible material and whose outer edge is reinforced to form a 95 ring of considerable cross sectional area, a disk to which the other extremity of the flexible fabric is applied, and an expanding spring located between the disk and the outer reinforced extremity of the hood, the bottom 100 having an opening through which the drill steel passes and in which it moves freely both longitudinally and rotatably, means for forming a dust tight joint around the drill steel comprising an exteriorly located sleeve 105 swiveled on the disk which is reinforced for the purpose, the sleeve having an opening through which the drill steel passes, said opening being shaped to conform approximately to the cross sectional area of the steel, 110 a gasket located in the sleeve, surrounding the drill steel, and shaped to fit the same, a second sleeve threaded into the first named sleeve and adapted to engage the gasket, whereby the latter is expanded both interiorly and exteriorly to form a dust tight joint, the bottom of the hood having a second opening for the escape of the rock cuttings, and a tubular member applied to the bottom and arranged to receive the cuttings 115 120

which pass through the said opening, and a hollow standard applied to the said tubular member and adapted to guide the rock cuttings downwardly therethrough, for the purpose set forth. 125

7. A dust collector for rock drills, comprising a hood composed of flexible material and whose outer edge is reinforced to form a ring of considerable cross sectional area, a disk to which the other extremity of the 130

flexible fabric is applied, and an expanding spring located between the disk and the outer reinforced extremity of the hood, the bottom having an opening through which the drill steel passes and in which it moves freely both longitudinally and rotatably, means for forming a dust tight joint around the drill steel comprising an exteriorly located sleeve swiveled on the disk which is reinforced for the purpose, the sleeve having an opening through which the drill steel passes, said opening being shaped to conform approximately to the cross sectional area of the steel, a gasket located in the sleeve, surrounding the drill steel, and shaped to fit the same, a second sleeve threaded into the first named sleeve and adapted to engage the gasket, whereby the latter is expanded both interiorly and exteriorly to form a dust tight joint, the bottom of the hood having a second opening for the escape of the rock cuttings, and a tubular member applied to the bottom and arranged to receive the cuttings which pass through the said opening, and a hollow standard applied to the said tubular member and adapted to guide the rock cuttings downwardly therethrough, the said standard consisting of two telescoping members to permit longitudinal adjustment to vary the height of the standard and means for securing the two standard parts in the adjusted position.

8. A dust collector for rock drills, comprising a hood composed of flexible material and whose outer edge is reinforced to form a ring of considerable cross section area, a disk to which the other extremity of the flexible fabric is applied, and an expanding spring located between the disk and the outer reinforced extremity of the hood, the bottom having an opening through which the drill steel passes and in which it moves freely both longitudinally and rotatably, means for forming a dust tight joint around the drill steel comprising an exteriorly located sleeve swiveled on the disk which is reinforced for the purpose, the sleeve having an opening through which the drill steel passes, said opening being shaped to conform approximately to the cross sectional area of the steel, a gasket located in the sleeve, surrounding the drill steel, and shaped to fit the same, a second sleeve threaded into the first named sleeve and adapted to engage the gasket, whereby the latter is expanded both interiorly and exteriorly to form a dust tight joint, the bottom of the hood having a second opening for the escape of the rock cuttings, and a tubular member applied to the bottom and arranged to receive the cuttings which pass through the said opening, and a hollow standard applied to the said tubular member and adapted to guide the rock cuttings downwardly therethrough, the said standard having a bottom opening for the escape of the rock cuttings.

9. A dust collector for rock drills, comprising a hood composed of flexible material and whose outer edge is reinforced to form a ring of considerable cross section area, a disk to which the other extremity of the flexible fabric is applied, and an expanding spring located between the disk and the outer reinforced extremity of the hood, the bottom having an opening through which the drill steel passes, and in which it moves freely both longitudinally and rotatably, means for forming a dust tight joint around the drill steel comprising an exteriorly located sleeve swiveled on the disk which is reinforced for the purpose, the sleeve having an opening through which the drill steel passes, said opening being shaped to conform approximately to the cross sectional area of the steel, a gasket located in the sleeve, surrounding the drill steel, and shaped to fit the same, a second sleeve threaded into the first named sleeve and adapted to engage the gasket, whereby the latter is expanded both interiorly and exteriorly to form a dust tight joint, the bottom of the hood having a second opening for the escape of the rock cuttings, and a tubular member applied to the bottom and arranged to receive the cuttings which pass through the said opening, and a hollow standard applied to the said tubular member and adapted to guide the rock cuttings downwardly therethrough, the said standard consisting of two telescoping members to permit longitudinal adjustment to vary the height of the standard and means for securing the two standard parts in the adjusted position.

9. A dust collector for rock drills, comprising a hood composed of flexible material and whose outer edge is reinforced to form a ring of considerable cross section area, a disk to which the other extremity of the flexible fabric is applied, and an expanding spring located between the disk and the outer reinforced extremity of the hood, the bottom having an opening through which the drill steel passes, and in which it moves freely both longitudinally and rotatably, means for forming a dust tight joint around the drill steel comprising an exteriorly located sleeve swiveled on the disk which is reinforced for the purpose, the sleeve having an opening through which the drill steel passes, said opening being shaped to conform approximately to the cross sectional area of the steel, a gasket located in the sleeve, surrounding the drill steel, and shaped to fit the same, a second sleeve threaded into the first named sleeve and adapted to engage the gasket, whereby the latter is expanded both interiorly and exteriorly to form a dust tight joint, the bottom of the hood having a second opening for the escape of the rock cuttings, and a tubular member applied to the bottom and arranged to receive the cuttings which pass through the said opening, and a hollow standard applied to the said tubular member and adapted to guide the rock cuttings downwardly therethrough, the said standard having a bottom opening for the escape of the rock cuttings.

In testimony whereof I affix my signature in presence of two witnesses.

FRANK RYLANDER.
